EDGAR B. SYMONS, OF MILWAUKEE, WISCONSIN.

CRUSHING-MACHINE.

1,013,626.

Specification of Letters Patent.

Patented Jan. 2, 1912.

Application filed December 19, 1908. Serial No. 468,306.

To all whom it may concern:

Be it known that I, EDGAR B. SYMONS, residing at Milwaukee, in the county of Milwaukee and State of Wisconsin, have 5 invented a certain new and useful Crushing-Machine, of which the following is a specification.

My invention relates to improvements in crushing machines in which the crushing 10 members rotate, and are given in their rotation a mutually reciprocative movement, thereby operating to crush stone or other material fed into the cavity between them.

The objects of my invention are, first, so to 15 improve the form of the opposing, crushing members so as to afford to material, during its travel from the mouth to the exit of the crushing cavity, a continually increasing crushing area, thereby allowing the material to spread during the process of its 20 reduction; second, to provide for the utilization of centrifugal force in maintaining a feeding pressure which shall vary with the speed and working capacity of the machine; third, to provide for changing the 25 length of the crushing stroke, or reciprocative movement of the opposing crushing members, as may be necessary or desirable to suit the various requirements or conditions 30 of work; fourth, to improve the method of taking up the wear of the crushing members, and also of adjusting their position relative to each other in order to change the size of the product; and fifth, to produce 35 a comparatively light, strong, durable and easily reparable crushing machine,—one especially efficient in the production of sand, or in the reduction of stone or like material to small particles.

40 Other minor objects appear in the description which follows.

My invention consists of the rotative reciprocative crushing plates or members which form a cavity between them.

45 It consists also in the means employed for supporting and rotating said plates; in the manner of determining and maintaining the angle of their respective planes of rotation; in the centrally located feeding orifice in association with the outwardly converging crushing cavity and peripheral exit; and also in the combinations of parts for effecting the objects desired as hereinafter specified and definitely pointed out in the claims.

50 In the following description reference is

had to the accompanying drawings in which:—

Figure 1 is a sectional plan of my machine with the feeding spout removed, and taken on the line M N of Fig. 2. Fig. 2 is 60 a side elevation of my machine. Fig. 3 is an end elevation having a portion of the outer casing broken away to show the circular form of the crushing plates, as further indicated by dotted line. Fig. 4 is a 65 detail elevation showing the interior of the cap which supports the crushing plate next to the feeding spout, and also the means employed to lock said cap in position. Fig. 5 is a side elevation of the cap 70 shown in Fig. 4.

Similar figures and letters are used to designate similar parts throughout the several views.

The hollow shaft 1, is provided at one 75 end with the flange A to which the cap 2 is adjustably secured by threaded attachment at B. The threaded ring portion of the cap 2, is divided at C, (see Figs. 4 and 5) and may be clamped securely to the 80 flange A, by means of the bolt 3, and the nut 4, thereby locking together parts 1, and 2, to form the outer rotative shell hereinafter alluded to, and referred to in the claims. Said outer shell is supported by, and is 85 rotative in bearings 5, and 6. The head-end, or disk-like portion of cap 2, is connected to said threaded ring portion by the arms 7, between which the openings 8 are provided to allow the escape of the crushed product. 90

95 9 is a belt-wheel keyed to shaft 1, for applying power to rotate said shell. Inside the hollow shaft 1, is mounted the shaft 10, which has its bowl-shaped end D, seated by ball and socket joint 11, in flange A. The outer end of shaft 10, is carried by the bearing 12, which is supported by and made laterally adjustable in the box-frame 13. The lateral adjustment of bearing 12, is effected by means of screw-bolts 14, which 100 connect it with 13. The collar 15, is secured to shaft 10, to prevent the longitudinal movement thereof. The opposing, circular, crushing plates 16, and 17, are removably secured respectively to the interior surface 105 of cap 2, and the bowl-shaped end D of shaft 10. The bolts 18 and the central screw 19 are employed to hold said crushing plates in position but any other means of attachment may be used as may be best suit- 110

ed to the form of said plates, either of which may be made in a single piece, as shown, or divided into parts constituting dies. The circular crushing plates 16, and 17, present 5 opposing dished or concave surfaces inclosing between them the crushing cavity 20, into which the central feed opening 21 through cap 2 and plate 16, is provided. The hood 22, which completely encircles the 10 cap 2 is held by parallel shafts 23, 23, in proper position to arrest the crushed product escaping from the crushing plates through the openings 8; said shafts being mounted in supports 24, 24 and 25, 25, comprising a part of the bed, or foundation 15 frame 26. Shafts 23, are made longitudinally adjustable in supports 24, and 25, thereby allowing the hood 22, to be shifted to suit the different adjustments of cap 2. 20 Set-screws 27, are employed to lock shafts 23, in any determined position. The cross-bar 28, secured to the hood 22, supports the feed-spout 29.

It is to be noted that the crushing plate 25 17, secured to the enlarged end of shaft 10 is so mounted within the outer rotative shell which carries plate 16, that the two crushing plates tend to rotate in unison, or concordantly, when power is applied to the belt- 30 wheel 9; and that this tendency of the two crushing plates to rotate together is due to the frictional contact of the ball and socket surfaces in the bearing 11, and is further due, when the machine is in operation, to 35 the connections formed between the two plates by stone or other material wedged between them. It is further obvious that when the axes of the two crushing plates are disposed at a given angle to each other, the 40 planes in which said plates rotate are respectively disposed at a like and equal angle. By this respectively oblique disposition of said plates they are caused to approach nearer to each other at 30 than at 31; and, likewise, 45 during their rotation, two opposing halves of said plates are constantly moving in a zone of mutual approach, while two opposing halves are moving in a zone of respective recession. This method of maintaining, during 50 operation, a reciprocating or crushing movement of said plates, whereby material carried with said plates in their rotation is forced into a diminishing cavity, and so crushed, is the conception of primary importance in my in- 55 vention.

When in the operation of my machine, power is applied to rotate the crushing members as described, stone, ore, or other material may be fed into the spout 29, whence 60 it falls within the crushing cavity until caught between the approaching rotating crushing plates and so crushed. At the same time said material is borne forward by said members in their rotation, whence 65 it derives a centrifugal force which operates

to carry it outwardly between said plates during their opening or divergent movement. That part of the material which has been sufficiently reduced in size to escape through the peripheral opening between said 70 plates, flies outwardly and is caught by the hood 22 and falls from the machine through exit 32; while pieces too large to escape in the manner described from the crushing cavity are impelled by centrifugal force to 75 travel outwardly after each successive crushing stroke toward said peripheral opening until sufficiently reduced to pass through it. The feeding is thus mainly accomplished under the pressure of centrifugal force which is obviously proportionate 80 to the speed of my machine. This affords an important advantage over other machines fed by the limited force of gravity which is often insufficient to force through wet or sticky material and so prevent clogging. Especially is clogging likely to occur in other machines when fine crushing is attempted both because no provision is made 85 for spreading the material over a crushing surface which presents an increasing area as reduction progresses, and because no provision is made for shortening the crushing stroke to suit the final reduction of small particles near the exit of the crushing 90 cavity. In my machine the crushing plates may be brought close together for fine crushing by turning the cap 2, on its threaded support at B, when said cap 2, is locked in 95 position by means described.

The crushing stroke, or reciprocating movement of the crushing members, may be shortened by turning the screw-bolts 14, to bring shaft 10, more nearly parallel to shaft 1. The angle between the respective planes of the rotative crushing members is thus reduced. These provisions for adjusting the relative position of the crushing plates, and for regulating their crushing movement to suit such adjustment in combination with the provision made for the stone to spread from the center to the circumference of a circular crushing area while in the process of reduction, especially adapt my machine for performing the work of fine crushing; while by reversing the adjustments described a coarse product may be readily obtained. By the arrangement of the two shafts with the ball and socket bearing an oil passage between them is provided for.

It will be understood that my invention relates for the most part to a crusher in which the shafts are mounted on a supporting frame in substantially a horizontal position. When in such a position the means for preventing the relative longitudinal movement of the two shafts is operative and of great importance. The particular means which I have shown are to be taken in a 130

sense as diagrammatically shown and it was my purpose to illustrate a method of construction whereby the shafts might be kept from relative longitudinal motion while the machine is in a horizontal position. As the stone passes between the two disks which must be so constructed as to present a central cavity the two faces of which are removed more widely than the faces at the discharge portion, it tends of course to wear the crushing surface. Hence the necessity of fastening the crushing disk surfaces so that their attaching portions are not subject to such wear. This may be done as illustrated by attaching one wearing surface at the center or opposite the feed opening and by attaching the other from the back so that the attaching devices lie entirely away from the effective crushing surfaces themselves. Some of the features of my invention are of course applicable to a machine in a vertical position. When the shafts are in a horizontal position the end thrust due to the weight of the inner shaft is avoided the feed is directed toward the center under conditions which make the feed by gravity carry the material outwardly and the whole operation of spouting the material into the machine and taking it from it is greatly facilitated.

Having thus described my invention what I claim as new and desire to secure by Letters Patent is:

1. The combination of two opposed crushing members, oblique to each other, and rotating in the same direction with means for varying their angle of obliquity, independent of the distance between them, said crushing members mounted each upon the end of a shaft, one of said shafts located within the other.

2. The combination of two opposed rotating crushing members oblique to each other, and rotating in the same direction with means for varying the distance between them independent of their angle of obliquity, said crushing members mounted each upon the end of a shaft, one of said shafts located within the other.

3. The combination of two opposed crushing members, oblique to each other, and rotating in the same direction with means for varying their angle of obliquity and the distance between them independent of each other, said crushing members mounted each upon the end of a shaft, one of said shafts located within the other.

4. The combination of two opposed rotating crushing members oblique to each other and rotating in the same direction with means for varying their angle of obliquity and separate means for varying the distance between them, said crushing members mounted each upon the end of a shaft, one of said shafts located within the other.

5. The combination of two opposed rotating crushing members rotating in the same direction and mounted oblique to each other, each upon the end of a shaft, one of said shafts mounted within the other and means for varying their angle of obliquity.

6. The combination of two opposed rotating crushing members rotating in the same direction and mounted oblique to each other, each upon the end of a shaft, one of said shafts mounted within the other, and means for varying the distance between them.

7. The combination of two opposed rotating crushing members rotating in the same direction and mounted oblique to each other, each upon the end of a shaft, one of said shafts mounted within the other and means for varying their angle of obliquity and the distance between them.

8. The combination of two opposed rotating crushing members rotating in the same direction and mounted oblique to each other, each upon the end of a shaft, one of said shafts mounted within the other and means for varying their angle of obliquity independent of the distance between them and separate means for varying the distance between them.

9. The combination of two opposed rotating crushing members one of them dish-shaped, and oblique to each other, with means for varying their angle of obliquity independent of the distance between them, said crushing members mounted each upon the end of a shaft, one of said shafts located within the other.

10. The combination of two opposed crushing members rotating in the same direction one of them dish-shaped and oblique to each other with means for varying the distance between them independent of their angle of obliquity, said crushing members mounted each upon the end of a shaft, one of said shafts located within the other.

11. The combination of two opposed rotating crushing members one of them dish-shaped, and oblique to each other with means for varying their angle of obliquity and the distance between them independently of each other, said crushing members mounted each upon the end of a shaft, one of said shafts located within the other.

12. The combination of two opposed rotating crushing members one of them dish-shaped and oblique to each other with means for varying their angle of obliquity and separate means for varying the distance between them, said crushing members mounted each upon the end of a shaft, one of said shafts located within the other.

13. A combination of two opposed rotating crushing members oblique to each other rotating in the same direction with means for varying their angle of obliquity, the distance between the crushing surfaces of said

members increasing from their center toward their peripheries inwardly at all points therealong.

14. A combination of two opposed rotating crushing members rotating in the same direction and oblique to each other with means for varying the distance between them, the distance between said crushing members being greater toward their center than toward their peripheries.

15. A combination of two opposed rotating crushing members rotating in the same direction and oblique to each other with means for varying their angle of obliquity and the distance between them, the distance between said crushing members being greater toward their center than toward their peripheries.

16. The combination of two opposed rotating crushing members rotating in the same direction and oblique to each other with means for varying their angle of obliquity and separate means for varying the distance between them, the distance between said crushing members being greater toward their center than toward their peripheries.

17. The combination of two opposed crushing members rotating in the same direction and oblique to each other and means for varying their angle of obliquity and supports for said crushing members mounted on the same side of both members, the distance between said crushing members being greater toward their center than toward their peripheries.

18. The combination of two opposed crushing members rotating in the same direction and oblique to each other with means for varying the distance between them and supports for said crushing members mounted on the same side of both members, the distance between said crushing members being greater toward their center than toward their peripheries.

19. The combination of two opposed crushing members rotating in the same direction and oblique to each other with means for varying their angle of obliquity and the distance between them and supports for said crushing members mounted on the same side of both members, the distance between said crushing members being greater toward their center than toward their peripheries.

20. The combination of two opposed crushing members rotating in the same direction and oblique to each other with means for varying their angle of obliquity separate means for varying the distance between them and supports for said crushing members mounted on the same side of both members, the distance between said crushing members being greater toward their center than toward their peripheries.

21. The combination of two opposed crushing members rotating in the same di-

rection and oblique to each other with means for varying their angle of obliquity said crushing members mounted on shafts, the distance between the crushing surfaces of said members increasing from their peripheries inwardly at all points therealong.

22. The combination of two opposed crushing members rotating in the same direction and oblique to each other with means for varying the distance between them said crushing members mounted on shafts, the distance between said crushing members being greater toward their center than toward their peripheries.

23. The combination of two opposed crushing members rotating in the same direction and oblique to each other with means for varying their angle of obliquity and the distance between them said crushing members mounted on shafts, the distance between said crushing members being greater toward their center than toward their peripheries.

24. The combination of two opposed crushing members rotating in the same direction and oblique to each other with means for varying their angle of obliquity and separate means for varying the distance between them said crushers mounted on shafts, the distance between said crushing members being greater toward their center than toward their peripheries.

25. The combination of two opposed crushing members rotating in the same direction and oblique to each other with means operable while the members are rotating for varying their angle of obliquity independent of the distance between them, the distance between said crushing members being greater toward their center than toward their peripheries.

26. The combination of two opposed crushing members rotating in the same direction and oblique to each other with means operable while the members are rotating for varying their angle of obliquity and separate means for varying the distance between them independent of each other, the distance between said crushing members being greater toward their center than toward their peripheries.

27. The combination of two opposed crushing members rotating in the same direction and oblique to each other with shafts on which they are mounted one hollow and containing the other, and means for varying their angle of obliquity comprising a bearing for one of the shafts adjusted transversely to their lengths, the distance between said crushing members being greater toward their center than toward their peripheries.

28. The combination of two opposed crushing members rotating in the same direction and oblique to each other with shafts on which they are mounted, also oblique to

each other, one hollow and containing the other and means for adjusting the obliquity of said shafts.

29. The combination of two opposed crushing members rotating in the same direction and oblique to each other with shafts on which they are mounted also oblique to each other and one within the other, the inner shaft provided with a bearing, and 10 means for moving said bearing laterally to vary the angle of obliquity of the two shafts.

30. The combination of two opposed crushing members rotating in the same direction and oblique to each other with shafts 15 on which they are mounted, also oblique to each other, one hollow and containing the other, the inner shaft projecting beyond the hollow shaft and provided with a bearing, and means for moving said bearing laterally 20 to vary the angle of obliquity of the two shafts.

31. The combination of two opposed crushing members rotating in the same direction and oblique to each other, suitable 25 supports therefor and a connection between the two including means for adjusting the distance between them independent of their angle of obliquity, said supports comprising a plurality of shafts one within the other.

32. The combination of two opposed dish-shaped crushing members rotating in the same direction and oblique to each other, suitable supports therefor, and a screw threaded connection whereby one may be 35 turned to vary the distance between them.

33. The combination of two opposed crushing members rotating in the same direction and oblique to each other, suitable supports therefor, a connection between the 40 two including means for adjusting the distance between them, and means for varying their angle of obliquity independent of the distance between them, said supports comprising a plurality of shafts mounted 45 one within the other.

34. The combination of two opposed rotating dish-shaped crushing members oblique to each other, suitable supports therefor, a screw threaded connection whereby one may be turned to vary the distance 50 between them, and means for varying their angle of obliquity.

35. The combination of two opposed rotating crushing members oblique to each other and rotating in the same direction, suitable supports therefor, a connection between the two including means for adjusting the distance between them independent of their angle of obliquity and means for 55 locking them in any desired position in which they may be adjusted, said supports comprising a plurality of shafts mounted one within the other.

36. The combination of two opposed rotating dish-shaped crushing members 60

oblique to each other, suitable supports therefor, a screw threaded connection whereby one may be turned to vary the distance between them, and means for locking them in any desired position in which they may be adjusted. 70

37. The combination of a hollow rotating shaft having a flanged end with a cap adjustably secured to said flanged end a crushing plate secured to said cap, an opposing crushing plate carried by a solid shaft mounted to rotate within said hollow shaft and means for adjusting the position of said solid shaft whereby its axis may be disposed at determinable angles to the axis of 80 said hollow shaft.

38. The combination of two opposed rotating crushing members, a hollow shaft for one and an inclosed rotating shaft for the other, the two shafts enlarged so as to 85 form a ball and socket bearing at one end and arranged so as to leave an open channel from the other end to such bearing.

39. The combination of two opposed rotating crushing members, suitable supports therefor, a frame on which the supports and crushing members are mounted, a hood surrounding said crushing members, and supports for the same longitudinally adjustable 90 on the frame.

40. The combination of two opposed rotating crushing members oblique to each other, mounted upon shafts one within the other, and means for preventing relative longitudinal displacement of such shafts. 10

41. The combination of two opposed rotating crushing members oblique to each other, mounted upon shafts one within the other, and means for preventing relative longitudinal displacement of such shafts, 10 such means comprising a ball and socket bearing at one end, a bearing for the free end of the inner shaft and a collar upon said shaft adapted to engage said bearing.

42. In a crushing machine containing two shafts one within the other, means for preventing relative longitudinal displacement of such shafts, comprising a bearing supporting the inner shaft, said inner shaft provided with a screw collar engaging the bearing at one end and adapted to draw the outer shaft against the other end of the bearing. 11

43. In a crushing machine containing two shafts one within the other, means for preventing relative longitudinal displacement 12 of such shafts, comprising a bearing surrounding the inner shaft and engaging at one end the outer shaft and at the other a collar upon the inner shaft.

44. The combination with a crushing machine comprising two opposed rotating crushing members, oblique to each other, of means for varying the length of the crushing stroke independent of the distance between the crushing members. 12

45. The combination with a crushing machine comprising two opposed rotating crushing members oblique to each other, of means for varying the effective crushing 5 opening independent of the distance between the crushing members.

46. In a crushing mill, the combination with two crushing disks which are inclined or tilted relative to each other, rotating 10 parts by which said disks are supported, a ring to which one of said disks is attached, said ring having a screw threaded connection with one of said rotating parts to enable the disk attached to said ring to be 15 adjusted toward and from the other disk to regulate the size of the crushed material.

47. In a crushing machine the combination of two opposed crushing members rotating in the same direction and mounted 20 oblique to each other, and means for varying the distance between them, the distance between said crushing members being greater toward their center than toward their peripheries.

48. In a crushing machine the combination of two opposed crushing members rotating in the same direction and oblique to each other two substantially horizontal shafts 25 one within the other upon which they are mounted, a supporting frame therefor and means for preventing relative longitudinal 30 displacement of such shafts.

49. In a crushing machine the combination of two opposed crushing members rotating in the same direction and oblique to 35 each other two substantially horizontal shafts one within the other upon which they are mounted, a supporting frame therefor and means for preventing relative longitudinal displacement of such shafts, said means comprising laterally projecting parts on the inner shaft between which the outer shaft is located. 40

50. In a crushing machine the combination of two opposed crushing members rotating in the same direction and oblique to each other with crushing surfaces and means for attaching the crushing surfaces to the crushing members, said means lying outside of the effective crushing surfaces. 45

51. In a crushing machine the combination of two opposed crushing members rotating in the same direction and oblique to each other with crushing surfaces and means for attaching the crushing surfaces to the crushing members, said means comprising a securing device at the center of one crushing surface and securing devices near the periphery and below the surface of the other. 55
